UNITED STATES PATENT OFFICE.

ERNEST LAUBINGER, OF WEIDEN, GERMANY.

DESIGN FOR A PLATE.

SPECIFICATION forming part of Design No. 25,404, dated April 21, 1896.

Application filed March 11, 1896. Serial No. 582,823. Term of patent 14 years.

To all whom it may concern:

Be it known that I, ERNEST LAUBINGER, a subject of the Emperor of Germany, residing at Weiden, in the Kingdom of Bavaria, Germany, have invented and produced a new and original Design for a Plate; and I do hereby declare the following to be a full, clear, and exact description of the same, reference being had to the accompanying drawing, forming a part thereof.

The figure is a top view of a plate embodying my design.

The leading features of my design consist of the line-borders upon the plate-rim and the radial ornaments upon the rim of the plate between the said line-borders.

In the drawing, A designates the plate with a rim, the latter having a wide solid-line border B upon the face of the rim near its outer edge. Upon the same surface of the rim and

near its outer edge is a lighter-line border C. These borders B and C are connected together by still lighter radial double lines D, which divide the surface of the rim inclosed by the said two borders into a series of angular spaces 25 E, certain of which spaces being divided by a diagonal line F. Each pair of lines D inclose an ornament G, which radiates from the inner to the outer border-line and imparts a distinct and ornate effect upon the surface of 30 the plate-rim.

What I claim is—

The design for a plate, substantially as herein shown and described.

In testimony whereof I affix my signature 35 in presence of two witnesses.

ERNEST LAUBINGER.
